[57] **CLAIM**

The ornamental design for a cartridge for a video game machine with seal printer, as shown and described.

DESCRIPTION

FIG. 1 is a front elevational view of a cartridge for a video game machine with seal printer showing our new design; FIG. 2 is a right side elevational view thereof, the left side elevational view being identical to the right side elevational view;

FIG. 3 is a top plan view thereof;
FIG. 4 is a bottom plan view thereof;
FIG. 5 is a rear elevational view thereof; and,
FIG. 6 is a perspective view thereof.
